ICE CREEPER

Charles B. Fisher, deceased, late of Williamsport, Pa., by Gertrude F. Fisher, administratrix, Williamsport, Pa.

Application May 14, 1946, Serial No. 669,636

3 Claims. (Cl. 36—7.6)

1

The present invention relates generally to improvements in detachable anti-slipping devices of the removable type to be worn on boots and shoes, and more specifically to ice creepers adapted for fastening, as by toe and heel straps to the boot or shoe, and when worn for use the creepers extend the full length of the boot or shoe from heel to toe.

While the removable creepers are adapted for use as safety devices for outdoor workers engaged in various occupations, they are particularly designed to prevent slipping on ice, snow, and other slippery surfaces and to insure a firm foothold on plane surfaces as well as on side-hills.

Because of the simplicity in construction of the component parts employed in the manufacture of the creepers the parts may with facility be produced in quantities at relatively low cost and readily assembled, and each creeper is then provided with a pair of standard make fastening straps that may readily be replaced if and when necessary.

The primary object of the invention is the provision of creepers that may with facility be applied to the shoes to present a neat appearance and insure comfort to the wearer; and by the utilization of a flexible or hinged sole-plate the wearer is enabled to walk with a natural step, and without tiring due to the presence of the creepers.

In the accompanying drawings one complete example of the physical embodiment of the invention is illustrated wherein parts are combined and arranged according to one mode thus far devised for the practical application of the principles of the invention, but it will be understood that various changes and alterations are contemplated and may be made in these exemplifying drawings and mechanical structures, within the scope of the appended claims without departing from the principles of the invention.

Figure 1 is a plan view of one of a pair of duplicate creepers in which the invention is embodied, the toe and heel straps being omitted, and parts of the chains being broken away for convenience of illustration.

Figure 2 is a view in side elevation of the creeper in Fig. 1 with the chains and side fastening members omitted.

Figure 3 is a perspective view of a conventional high shoe or boot with one of the creepers strapped thereto.

Figure 4 is a transverse vertical sectional view as at line 4—4 of Fig. 1.

2

In carrying out the invention and as illustrated in the drawings a central longitudinally extending flat metallic bar or narrow base-plate 1 is utilized, which terminates at its rear end in an upright integral post 2, and beneath this base bar a somewhat triangular or tapering heel plate 3 is riveted as at 4, 4. Projecting laterally from the forward end of the heel plate are arranged two aligned angle brackets 5, 5, riveted at 4, 4 on the top of the heel plate, and these angle brackets are fashioned with integral upright posts 6, 6, similar to the rear post 2.

The rear post 2 and the two side posts 6, 6, are united by a U-shaped open front heel brace, here shown as consisting of two rounded comparatively thin metallic straps 7, 7, and these straps, which may be of resilient metal, are attached at their ends by rivets 4 to the two side posts and the rear post.

20 The front end of the base bar 1 is securely riveted on top of a tapering sole-plate 8, and a toe-plate or ball-plate 9 is hinged, flexible connected, or articulated with the sole plate by a hinge 10, the blades or wings of the hinge being secured by rivets 4 to the respective plates 8 and 9. The sole-plate and the toe-plate are both of triangular formation with their widest portions united by the hinge joint, and this jointed connection between the plates approximates the articulation of the natural foot to permit a forward and backward rocking motion, so that the weight of the wearer may be supported on the ball of the foot when the heel is raised, as in walking.

35 The heel plate, the sole plate, and the toe plate, together with the hinge wings are all firmly united with the base bar to prevent lateral rocking of the creeper, as well as to prevent lateral rocking of the boot or shoe when the wearer is walking.

Each of the plates 3, 8, and 9 is provided with integral calks to prevent slipping laterally as well as forwardly and backwardly, and these calks, which are arranged in pairs, are struck or bent 45 from the plates in predetermined positions with respect to the plates.

The three pairs of calks that prevent forward and backward slipping, and hereinafter referred to as longitudinal calks, are indicated by the number 11, and they are located at the front of the toe-plate, the rear of the sole-plate; and the rear end of the heel plate, just in front of the rear post 2.

50 The three pairs of calks that prevent lateral slipping are indicated by the number 12, and

they project from the widest portions of the several plates to insure a wide bearing for the creepers.

For co-action with the U-shaped heel brace 1, in fastening the heel portion of the creeper to the shoe or boot, a heel strap or ankle strap 14 is employed, as in Fig. 3, which strap may be of leather, fabric, or other desirable material, and provided with a buckle 15, and the strap, preferably, is doubled to connect two metallic loops as 16, 16, each of which is mounted by a bracket 17 on a lateral or side post 6 and secured by the rivet 4. The bracket and loop are preferably arranged at an angle to the plane of the U-shaped brace so that the strap may extend smoothly across the front portion of the ankle and securely fasten the heel of the creeper to the boot or shoe.

As indicated in Fig. 3 the toe portion of the creeper is fastened by means of a strap 18 and its buckle 19, the strap being looped or doubled across the toe of the boot to unite a pair of metallic yokes 20 and 21 each having eyes 22 at their front and rear ends. The yokes are loosely or flexibly connected to the toe plate and the sole plate, respectively, by chains 23 and 24, and the plates are fashioned with holes 25 for attachment of the chains.

The chains are of suitable length to permit the yokes being lifted up and positioned parallel with the sides of the boot or shoe for connection by the doubled or looped strap 18, and it will be noted that the chains or flexible connections at the ends of the yokes or bridge bars 20, 21, are connected in pairs to the plates.

The pair of chains 24, 24, are connected to the sole plate 8 and the pair of chains 23, 23, are connected to the toe plate 9, the chains 23 and 24 being anchored to the plates at opposite sides of the transversely extending hinge joint 10, in order to provide a wide and substantial structure that permits flexing of the sole portion of the creeper, and at the same time prevents displacement of parts.

The side yokes or bridge bars 20, 21, at the toe portion of the creeper perform the same functions as the U-shaped brace 1 at the heel portion of the creeper, and the chains, which may be adjusted as to length, readily adapt the creeper to different widths of boots or shoes, while the U-shaped brace is of a size to accommodate a standard type of heel.

As an aid to the longitudinal and lateral calks, the base bar 1 may be provided with additional antislipping devices in the nature of short spikes or studs S, S, that are riveted in holes provided therefor by turning down the heads S' of the studs.

These studs or spikes located between the heel plate and the sole plate are arranged at opposite sides of the center line of the bar, or staggered, and as best seen in Fig. 2 the pointed ends of the tapered studs terminate short of the ground line, to act as auxiliary supports for the creeper when needed.

While only one of the creepers has been illustrated and described, it will be understood of

course that the creepers are employed in pairs, and inasmuch as the creepers are all of similar construction and interchangeable for use with either the right foot or the left foot a selection is not necessary in putting them on the boots or shoes.

From this description taken in connection with the drawings, it will be apparent that the creepers may be put on the boots of a wearer and the fastening straps secured in manner similar to the application of a pair of skates to the booted feet of a skater, and with equal facility the creepers may be removed by loosening the two buckled straps of each creeper. They may be firmly secured to the boots to insure comfort to the wearer, and they are efficient in the performance of their functions without materially impeding the foot-action of the wearer in his natural gait or walk.

Having thus fully described the invention, what is claimed herein and desired to be secured by Letters Patent is:

1. In a creeper as described, the combination, with a longitudinally extending base member and a sole-plate rigid therewith, of a toe-plate, a transversely arranged hinge joint between said plates, a pair of rigid strap-yokes arranged transversely of the hinge joint, and flexible connections between said yokes and the respective plates.

2. In a creeper as described, the combination, with a longitudinally extending base-bar, and a sole-plate rigid therewith, of a toe-plate, a transversely arranged hinge joint between said plates, a pair of laterally extending chains attached to each plate, and a pair of strap-yokes at opposite sides of the plates connecting said chains in pairs.

3. In a creeper as described, the combination, with a longitudinally extending base-bar having an upright end-post, a heel plate rigid with the base bar and a pair of side posts rigid with said plate, a U-shaped heel-brace mounted in said posts, and means for attaching an ankle-strap to the side posts, of a sole-plate rigid with the bar, a toe-plate hinged to the sole-plate, a pair of aligned laterally extending chains connected to each of said sole and toe plates, and a pair of side strap-yokes each connected at its opposite ends to the outer ends of a pair of said chains.

GERTRUDE F. FISHER.

Administratrix for Charles B. Fisher, Deceased.
